CLAIM

The ornamental design for a ball for playing soccer (football), as shown and described.

DESCRIPTION

FIG. 1 is a front elevation of a ball showing the new design;
FIG. 2 is a plan view rotated 90 degrees in a counter-clockwise direction of said ball;

FIG. 3 is a side elevation rotated 90 degrees in a counter-clockwise direction of said ball; and,

FIG. 4 is a perspective view of said ball.
